Jacob M. Stouder INVENTOR

BY H. G. Burns

ATTORNEY

UNITED STATES PATENT OFFICE.

JACOB M. STOUDER, OF FORT WAYNE, INDIANA.

NOZZLE.

SPECIFICATION forming part of Letters Patent No. 729,974, dated June 2, 1903.

Application filed July 16, 1902. Serial No. 115,749. (No model.)

To all whom it may concern:

Be it known that I, JACOB M. STOUDER, a citizen of the United States, residing at Fort Wayne, in the county of Allen and State of Indiana, have invented certain new and useful Improvements in Nozzles; and I do declare the following to be a full, clear, and exact description of the invention, such as will enable others skilled in the art to which it app pertains to make and use the same, reference being had to the accompanying drawing, and to the figures of reference marked thereon, which forms a part of this specification.

My invention relates to improvements in nozzles by which water is discharged in either a spray or a straight stream; and the object of my improvement is to afford adjusting means whereby the water may be discharged from the nozzle in a spray or a straight stream or both simultaneously.

I accomplish my object by the construction illustrated in the accompanying drawing, which is a longitudinal section through the nozzle.

This invention consists of a body 1, having a threaded shank 5 and a central discharge-spout 2, the bore 3 of which extends entirely through the nozzle. An adjustable barrel 4 is engaged by means of threads upon the shank 5 and extends over the spout 2 to a point near the end thereof. A collar 9, having a flaring exterior surface, is mounted upon the tip end of the spout 2 with its lowermost flaring portion immediately above the open end of the barrel 4. The said collar is adapted when the barrel is properly adjusted to close or partially close the end of said barrel. A packing-ring 7 is arranged about the shank 5 and within the barrel 4 to prevent leakage. A three-way valve 11 is arranged within the body 1 and is adapted to be turned therein. A side port 8 is made in the body and leads from the side of said valve up

through the shank 5 and opens to one side of the spout 2 and within the barrel 4. 45

In operation the nozzle is attached to a suitable hose and the valve is turned to direct the flow of water either directly through the bore 3 of the spout or into the side port 8, or both, as can obviously be done. The water flowing through the barrel is discharged therefrom through the annular opening 10 between the collar 9 and the end of the barrel, thus emitting the water therefrom in a spray, which can be readily varied by adjusting the barrel 55 upon the shank, or the flow of water from the barrel may be checked entirely by closing the opening 10 by the same means of adjustment. Thus I have provided two separate means of controlling and directing the flow of water. 60

Having described my invention, what I claim as new, and desire to secure by Letters Patent, is—

1. A nozzle comprising a body having a central discharge-spout; an adjustable barrel 65 mounted upon said body and surrounding said spout; a collar mounted upon the tip of said spout coincident with the opening at the end of the barrel; a three-way valve arranged in said body communicating with the spout; 70 and a side port communicating with the valve and leading into the barrel.

2. A nozzle comprising a body; a discharge-spout leading therefrom; a barrel mounted upon the body surrounding the spout and 75 having an opening at its end; a three-way valve arranged in the body communicating with the spout; and a side port communicating with the valve and leading into the barrel.

In testimony whereof I affix my signature 80 in presence of two witnesses.

JACOB M. STOUDER.
